UNITED STATES PATENT OFFICE

126,889

DESIGN FOR AN EMBROIDERED FABRIC

Otto Hallbauer, West Englewood, N. J.

Application November 27, 1940, Serial No. 96,875

Term of patent 3½ years

To all whom it may concern:

Be it known that I, Otto Hallbauer, a citizen of the United States, residing at West Englewood, Bergen County, and State of New Jersey, have invented a new, original, and ornamental Design for an Embroidered Fabric, of which the following is a specification, reference being had to the accompanying drawing, forming part thereof.

The figure is a plan view of an embroidered fabric showing my new design.

The characteristic features of the embroidered fabric of my design reside in the series of centrally disposed medallions in combination with the specific serrated border having alternately large and small eyelet openings, all as shown.

I claim:

The ornamental design for an embroidered fabric, substantially as shown and described.

OTTO HALBAUER.
